ATTORNEY.

UNITED STATES PATENT OFFICE.

FREDERICK W. DRESSEL, OF NEW YORK, N. Y.

DESIGN FOR A LAMP-BURNER.

SPECIFICATION forming part of Design No. 28,417, dated March 29, 1898.

Application filed December 28, 1897. Serial No. 664,125. Term of patent 7 years.

To all whom it may concern:

Be it known that I, FREDERICK W. DRESSEL, a citizen of the United States, residing in the city, county, and State of New York, have invented and produced a new and original Design for a Lamp-Burner, of which the following is a specification.

In the accompanying drawings, forming a part hereof, Figure 1 is a plan view, and Fig. 2 a side elevation, of my new design for a lamp-burner.

Similar numerals of reference, wherever they occur, indicate corresponding parts in both figures.

As shown in the drawings, the leading or material features of my design consist in the

spreader 1, having flat side supports 2, open top 3, and downwardly and outwardly extending straight sides 4, these parts being located above and mounted upon the lower portion 5 of the burner, which is provided with alternate perforations 6 and 7.

Having now described my invention, what I claim as new, and desire to secure by Letters Patent, is—

The design for a lamp-burner as herein shown and described.

FREDERICK W. DRESSEL.
